(57) CLAIM

The ornamental design for a pontoon boat with elevated front wave guard, as shown and described.

DESCRIPTION

FIG. 1 is an upper isometric view of a pontoon boat with elevated front wave guard.

FIG. 2 is a lower isometric view of the pontoon boat with elevated front wave guard of FIG. 1.

FIG. 3 is a top side view of the pontoon boat with elevated front wave guard of FIG. 1.

FIG. 4 is a bottom side view of the pontoon boat with elevated front wave guard of FIG. 1.

FIG. 5 is a left side view of the pontoon boat with elevated front wave guard of FIG. 1.

FIG. 6 is a right side view of the pontoon boat with elevated front wave guard of FIG. 1.

FIG. 7 is a front side view of the pontoon boat with elevated front wave guard of FIG. 1.

FIG. 8 is a rear side view of the pontoon boat with elevated front wave guard of FIG. 1.

FIG. 9 is an upper isometric view of another pontoon boat with elevated front wave guard.

FIG. 10 is a lower isometric view of the pontoon boat with elevated front wave guard of FIG. 9.

FIG. 11 is a top side view of the pontoon boat with elevated front wave guard of FIG. 9.

FIG. 12 is a bottom side view of the pontoon boat with elevated front wave guard of FIG. 9.

FIG. 13 is a left side view of the pontoon boat with elevated front wave guard of FIG. 9.

FIG. 14 is a right side view of the pontoon boat with elevated front wave guard of FIG. 9.

FIG. 15 is a front side view of the pontoon boat with elevated front wave guard of FIG. 9; and,

FIG. 16 is a rear side view of the pontoon boat with elevated front wave guard of FIG. 9.

The broken lines are for the purpose of illustrating portions of the article that form no part of the claim.
